UNITED STATES PATENT OFFICE

ROBERT UHDE, OF KASSEL-WILHELMSHOHE, GERMANY, ASSIGNOR TO SCHMIDT 'SCHE HEISSDAMPF-GESELLSCHAFT MIT BESCHRÄNKTER HAFTUNG, OF KASSEL-WILHELMSHOHE, GERMANY, A CORPORATION OF GERMANY

HEAT TRANSFERRER

Application filed December 19, 1928, Serial No. 327,033, and in Germany December 29, 1927.

The invention relates to heat transmitters and while generally applicable is specially designed for the superheating of steam.

The object of the invention is to construct a heat transmittor, such that when applied, e. g., to the superheating of interstage steam, large quantities of steam can be highly superheated without the interstage superheater attaining undesirable large dimensions.

10 In the interstage superheaters of modern steam power plants, the high-pressure steam which serves as the heating medium is led through heating elements arranged in a container through which passes the steam to be superheated.

According to the present invention, each of a series of like heating elements arranged side by side consists of two or more tubes 20 connected in parallel, which for a part of their length are formed as helical coils and are so assembled that they provide a continuous coil sub-divided to correspond with the number of tubes in the individual 25 elements.

With the new heat transmittor, large quantities of steam can be passed through not only the heating elements, but also through the container in which they are 30 arranged, and the latter steam superheated to a high degree.

By reason of the fact that all the heating elements are alike and that each single heating element consists of two or more tubes 35 arranged in parallel, which together form a continuous coil, a very large heating surface is provided and as, in addition, the steam in all the tubes passes over only the same comparatively short length of path, its 40 heat content is utilized under the most favourable conditions.

Referring to the accompanying drawings, different forms of the invention are shown 45 by way of example;

Figure 1 is a vertical central section of a heat-transferring device according to my invention, the heating elements in the central row only being shown for the sake of clear- 50 ness;

Figure 2 is a horizontal section on line II-II of Fig. 1;

Figures 3 and 4 show one form of heating element in side elevations respectively at right angles to one another;

55

Figure 5 shows a modified form of heating element in side elevation;

Figure 6 being a cross-section on line VI-VI of Figure 5, and

Figure 7 shows another form of heating 60 element in side elevation.

Referring first to Figures 1 and 2, the casing, 18, containing the heating elements, is closed at the top by a plate, 19, and at the bottom by a plate, 20. To the plate, 19, a 65 cover, 21, is fastened, provided with a chamber, 22, and a branch, 23, leading to that chamber. A similar cover, 24, provided with a chamber, 25, and a branch, 26, is secured to the bottom of the casing, 18. The 70 inlet and outlet ends of the heating elements are secured into corresponding holes in the plates, 19, and 20, and communicate with the chambers, 22, and 25, respectively. The superheating medium enters through the 75 branch 23 into the chamber, 22, passes through the heating elements arranged side by side and leaves the device through chamber, 25, and branch, 26. The medium to be superheated enters the casing, 18, 80 through the connection, 27, and leaves the casing through the connection, 28.

The heating elements arranged in the casing, 1, are formed partly as helical coils and partly as straight lengths, assembled as 85 shown by way of example in the drawings.

The heating element shown in Figures 3 and 4 consists of two tubes, 1, 2 and 3, 4, connected in parallel.

The one tube as regards its upper half is 90 wound into a helical coil, 1, and at the middle point in the length of the heating element changes over to a straight length of tube 2, by means of a short bend, 5, running inwards to the axis of the element. 95 The second tube, 3, 4, on the contrary, is straight as regards the upper half, 3, of the element and by means of a short bend, 6 running outwards from the axis of the element, changes over to a helical coil, 4. In 100

each case, the straight length of the one tube lies within the helical convolutions of the tube. At the upper and lower ends of the heating element, the two tubes are respectively connected by the Y-pieces, 7 and 8.

5 The heating element shown in Figures 3 and 4 is of somewhat similar construction as those arranged in the casing, 18, of Figures 1 and 2. This element is composed of three tubes connected in parallel. The first tube 10 consists of the upper helically-wound coil, 9, and the straight length of tube, 10, connected to it below; the second tube comprises the lower coil, 11, and the straight length of tube, 12, connected to it above; and the 15 third tube is formed into helically-wound middle part, 13, and the straight lengths, 14, 15, connected to it respectively above and below.

20 At their upper ends the tubes are connected to the three-limbed Y-piece, 16, and at their lower ends to the similar Y-piece, 17, the tubular stems of the Y-piece serving to connect the heating elements to the header or the like to or from which the heat carrier 25 is led. By the use of such Y-pieces, an undue multiplication of connections is avoided.

20 The straight lengths of tube in the modifications described are all arranged within 30 the helical convolutions of the heating element. In some cases it might be preferable to have a part of the straight lengths lying outside the convolutions. The heating element of Figure 7, which is composed of 35 three tubes connected in parallel, has, for example, the straight lengths of tube 12' and 15' arranged outside the convolutions.

30 In Figures 1 and 2 the individual heating elements, connected in parallel, are arranged 40 in a circle side by side in the container, 18. Instead of the circular arrangement shown, the heating elements may also be disposed in rows, for example, in parallel formation. The essential requirement is that all the individual heating elements are connected in 45 parallel so that the highly-superheated steam serving as heat carrier flows through all the elements under the same conditions.

30 By the sub-division of the like individual 50 heating elements into tubes connected in parallel and helically wound for only a part of their length, the resistance to flow which the heat carrier has to overcome is substantially less than if each tube were formed as 55 a coil for its whole length; thus, the resistance to flow in the form of the invention shown in Figures 1 and 2 is approximately one-half and in the form of the invention shown in Figures 3 and 4, one-third as much 60 as in a single helical coil of the same length.

50 Transfer of heat, which occurs for the most part in the helical coils, is comparatively large as these coils, notwithstanding their sub-division, extend continuously over 65 the length of the heating element.

In addition, the straight lengths of tube lying within the helical convolutions contribute to the quantity of heat transferred so that the dead space which would otherwise be present within the coils is utilized.

70 What I claim is:

1. In a heat-transferrer of the class described, the combination of a casing, an inlet to and an outlet from said casing, a plurality of like heating elements arranged side by side in said casing, and an inlet connection and an outlet connection communicating with said heating elements, each of which elements consists of two or more tubes arranged in parallel, which are formed partly as helical coils and partly as straight lengths, and are so assembled that they provide a coil sub-divided to correspond with the number of tubes of the individual elements.

80 2. In a heat-transferrer of the class described the combination of a casing, an inlet to and an outlet from said casing, a plurality of like heating elements arranged side by side in said casing and an inlet connection and an outlet connection communicating with said heating elements, each of which elements consists of two or more tubes arranged in parallel, which are formed partly as helical coils and partly as straight lengths, and are so assembled that they provide a coil sub-divided to correspond with the number of tubes of the individual elements, said straight lengths of the tubes passing through 90 the convolutions of the helical coils.

95 3. In a heat-transferrer as defined in claim 1, the said tubes forming the compound coil being connected at each end of the heating element to a common Y-piece.

100 In testimony whereof I have affixed my 105 signature.

ROBERT UHDE.
